CONTAINER CLOSURE

Curtis M. Koster, San Francisco, Calif., assignor,
by mesne assignments, to Breda, Inc., San
Francisco, Calif., a corporation of California

Application October 9, 1948, Serial No. 53,650

3 Claims. (Cl. 215—45)

1 2

The present invention relates to closures for containers and more particularly to bottle and jar caps and closures and the like, and has as its principal object the provision of such closures which can quickly and effectively seal the bottle contents and which can be utilized for an indefinite number of times, thus permitting the bottle to be resealed after portions of its contents have been removed.

Closures of this general type have been disclosed in the prior art, but such devices have generally been of the type in which a sealing ring is mounted directly on the cap, and have had numerous disadvantages, such as surface exposure of moving parts and have become distorted after continued use rendering cooperation of the functioning parts difficult and eventually affecting the sealing efficiency.

The present invention is a continuation-in-part of my copending application Serial No. 788,131, filed November 26, 1947.

In accordance with the present invention, a closure is provided which obviates many of the disadvantages of the prior art and provides a cap having a readily rotatable inner sealing member which may be easily applied and removed and which at the same time functions to effect an efficient seal. These results are obtained by providing an outer cap member which may be made of any suitable metal or plastic having the requisite strength and an inner member concentric therewith and rotatable therein which carries a sealing means and which is designed to permit rotary bearing members to function simultaneously to open or close means which engage the neck of the bottle while at the same time these bearing means serve to facilitate relative rotation between the inner and outer members.

The invention is described in detail in the accompanying drawings wherein Fig. 1 is a vertical cross section taken through the center of a bottle cap shown in position engaging the top of a bottle.

Fig. 2 is a horizontal cross section through the cap taken along lines 2—2 of Fig. 1.

Fig. 3 is a view in elevation of the cap looking from the bottom thereof.

Fig. 4 is an elevational exploded view of the disassembled cap.

Fig. 5 is a view in elevation of a disassembled cap showing a modified form of the invention.

Referring to the drawings and describing first the form of invention illustrated in Figs. 1 to 4 inclusive, and more particularly in connection

with the respective elements as illustrated in Fig. 1, reference numeral 10 represents the outer cap member which is preferably continuous in structure and may be stamped from sheet metal or molded from plastic. Positioned within the cap member and concentric therewith is inner member 11 which preferably is spaced from cap 10 except at point 12 where the outer cap is engaged by an axially dished out or protruding portion 13 which is designed to engage the cap and form a center of rotation or bearing surface about which the inner cap may rotate. Member 11 has a plurality of prongs 14 extending at right angles thereto and whose function will be described further below. A plurality of channeled clamping members 15 which are designed to be forced into engagement with the neck of the closure are preferably provided with ribs or bosses 16 for the purpose of more firmly engaging the closure. Each channeled member 15 is provided at one end thereof with a normally vertically channeled portion 17 which is designed to fit over and engage prongs 14. The normally horizontal channeled portion 18 is formed so that its opening faces the outer cap. Small roller bearings 19 are provided and designed so as to fit within channels 18 and ride therein between members 15 and the inside wall of the outer cap member 10, or the walls of an internally secured ring 25 as referred to below. These bearing members are held in place by spacing members 20 which are curved to conform to the curvature of the outer cap and are designed to fit into channels 18. Each of these spacing members has at one end a bent-over portion 21 which is designed to engage one wall of the vertical channel 17 as shown at 22. The other end of each spacing member 20 is preferably bent in a curved manner as shown in 23, with the bearings 19 being positioned between opposite ends 21 and 23 of respective spacing members.

Positioned within inner member 11 is a gasket or sealing means 24 which may be made of cork or rubber or the like. This is preferably secured to the bottom portion of 11 by means of an adhesive. The entire assembly is held in place by a ring member 25 which has an inwardly extending flanged portion 26 and which is designed to hold the rotatable elements associated with the inner member within outer cap 10. Ring 25 is compressed into tight engagement with the outer cap in order to keep it from moving and is also held in position by lips 27 55 along the bottom edge of cap 10, which are bent

inward slightly to engage and clamp the inner ring. The wall of the ring engaging the cap may be wide enough to form the inner surface engaged by the bearings, or it may be narrow, in which case the bearings will engage the inner wall of the cap directly. If desired, the ring may be omitted and the bottom edge of the cap bent inward in order to hold the inner elements in place.

When the cap is in open position, that is, before it is first applied to the opening in the bottle or other container, the relative positions of the bearings and clamping members are shown in bottom elevation in Fig. 3. There the bearings 19 are at the end of the channel which is anchored to prong 14 by engaging vertical channel 17 and rest against the wall 21 of members 20. Clamping members 15 are in a retracted position. In use the cap is inserted over the neck of the bottle with the gasket material 24 engaging the top of the bottle as shown at 28 in Fig. 1. A slight amount of pressure is applied and the frictional resistance between the gasket material and the top of the bottle will force inner member 11 and its associated parts to remain at rest while the outer cap is rotated. At the same time the bearing members 19 are rolled along the track or channel 18 of each member 15, to the position shown in Fig. 2. The channels 18 of member 15 are designed to have a different curvature from the outer cap so that each channel member will in fact be a cam and will function like a cam surface to force the clamping member together with boss 16 inward to engage the neck of the container as the bearing rolls up the channel. This can be accomplished by making the clamping member have a slightly greater curvature toward the end or free portion thereof, or by building up the channel toward its end so that the spacing between the inside of the channel and the outer cap will be progressively decreased toward the end thereof. The bearing is stopped against further circumferential movement, when rigid clamping has occurred, or by engagement of the rolled portion 23 of spacing member 20 with wall 22a of the vertical channel 17.

In assembling the cap, inner member or spider 11 is held in a fixed position in a jig or other suitable device. The four channeled cam members 15 are now placed in position with channels 17 engaging arms 14. Spring-like spacing members 20 are then placed in position and the four bearings 19 are then placed in the channels. Ring 25 is then placed over the spider with its assembled parts and the entire assembly inserted in position in the outer cap. Following this the ring 25 is clamped into position with outer cap 10 in a closing die. The gasket is affixed to the interior of the spider by means of cement after assembly.

To recapitulate, when the cap as shown in Fig. 3 is applied over the neck of a bottle and rotated in a counterclockwise direction (looking into the open end) or in a clockwise direction looking down from the top of the cap, and vertical pressure is simultaneously applied to force the gasket into engagement, roller bearings 19 ride along the channel 18 and force the bosses 16 into firm engagement with the neck of the bottle thus clamping the gasket material in place. When the cap is to be applied to bottles or the like having a rib or lip around the outer edge of the opening, as shown at 28 in Fig. 1, the clamping members are so designed that the bosses will fit just under the lip so as to give firm vertical as well as horizontal engagement with the neck of the bottle.

In a preferred form of my invention, inner member 11 is provided with a depressed portion or ring-like structure 30, which is formed concentric with raised portion 12 and has a diameter somewhat less than the inside of the bottle or other container to be closed. This is for the purpose of permitting the sealing member or gasket to be forced into engagement with the inside edge of the container opening as shown at 31, in addition to the top edge. In this way, improved sealing is effected.

While the outer cap may be made of plastic, sheet metal, such as sheet steel, is preferable for this as well as the other elements of the inner members. The bearings may be of steel or other known bearing material. Instead of roller bearings, ball bearings may be used and the channels designed so as to accommodate them.

In the modification of the invention which is illustrated in Fig. 5, inner member 11' is constructed with clamping members 15' made integral therewith by slotting and stamping from sheet metal with bosses 16' formed therein. A separate ring member 29 is provided which fits around and over the clamping members and between the inside walls of outer cap 10' and the inner member. A plurality of prongs extend inward at right angles to the ring member and are secured thereto. These prongs are short shafts on which roller bearings 19' are mounted, being kept in place by offsetting the ends of the shaft, or otherwise. When the cap is applied to a bottle the outer cap bearing ring 29 and its associated bearings 19' are also rotated, the bearings rolling along prongs 15' toward their free ends thus forcing them inward so that bosses 16' will clamp and engage the neck of the bottle. As shown in the drawing, the free ends of the prongs are curved slightly outward to serve as stops for the bearings.

As is readily apparent, the provision of bearings in rolling engagement with the channeled cam members and with the inner surface of the outer cap, permits free relative motion of the outer cap with simultaneous clamping of the cam members against the neck of the container. Thus there is no binding and less friction while at the same time enabling the application of substantial pressure in the clamping process.

While the foregoing specification refers to specific embodiments of the invention, it is understood that it is intended to comprehend within the scope of the invention such modifications as shall occur to those skilled in the art and within the scope of the appended claims.

53 I claim:

1. A closure member for containers which comprises an outer cap member having a depending cylindrical flange portion, an inner member concentric therewith and spaced therefrom and being rotatably positioned within said outer cap member, said inner member having a plurality of depending arms attached thereto, a channeled cam member attached to each arm for pivotal movement about a vertical axis, the channel 60 thereof facing the inside wall of the cylindrical flange portion and the cam portion extending radially inwardly, said channeled cam members being spaced circumferentially to define an opening into which the neck of the container 65 may be inserted, a rotary bearing positioned in each channeled cam member between the cam portion and the depending flange to provide rolling bearing contact between the back of the cam portion and the outer cap, a gasket member 70 affixed within the inner member adapted to en-

gage the top of the container when the closure is inserted thereover and to hold the inner member against rotation while a rotary movement is imparted to the outer cap member to cause the rotary bearings to ride in the channels of the channeled cam members and force the cam portions inwardly to engage the neck of the container.

2. A closure member for containers which comprises an outer cap member having a depending cylindrical flange portion, an inner member concentric therewith and spaced therefrom and having a peaked central portion axially engaging the top of said outer cap member and a plurality of depending arms attached thereto, a channeled cam member attached to each arm for pivotal movement about a vertical axis, the channel thereof facing the inside wall of the cylindrical flange portion and the cam portion extending radially inwardly, said channeled cam members being spaced circumferentially to define an opening into which the neck of the container may be inserted, a rotary bearing positioned in each channeled cam member between the cam portion and the depending flange to provide rolling bearing contact between the back of the cam portion and the outer cap, a gasket member affixed within the inner member adapted to engage the top of the container when the closure is inserted thereover and to hold the inner member against rotation while a rotary movement is imparted to the outer cap member to cause the rotary bearings to ride in the channels of the channeled cam members and force the cam portions inwardly to engage the neck of the container.

3. A closure member for containers comprising an outer cap member having a depending cylindrical flange portion, an inner member concentric therewith and spaced therefrom and mounted for relative rotational movement with respect to the outer cap member, a plurality of

5 circumferentially spaced arms depending from said inner member in substantially parallel relation to the flange portion of the outer cap member, a channeled arcuate arm for each of said depending arms having a free pivotal attachment therewith permitting said arms to be pivoted about vertical axes, said arcuate arms having their channels facing the flange of the outer cap and being spaced circumferentially to define an opening into which the neck of a container may be inserted, a gasket member positioned within the inner member and adapted to engage the top of a container and hold the inner member against rotation when a rotary movement is imparted to the outer cap member, and means residing within the channels of said arms and movable with the outer cap member upon rotative movement of said cap member to cam said arcuate arms inwardly to engage the neck of a container.
